UNITED STATES PATENT OFFICE.

EDWARD S. HUFF, OF DETROIT, MICHIGAN, ASSIGNOR, BY MESNE ASSIGNMENTS, TO THE SIMMS MAGNETO COMPANY, A CORPORATION OF NEW JERSEY.

ENGINE-STARTER.

1,300,970.

Specification of Letters Patent. Patented Apr. 15, 1919.

Application filed November 16, 1914. Serial No. 872,296.

To all whom it may concern:

Be it known that I, EDWARD S. HUFF, a citizen of the United States, residing at Detroit, county of Wayne, State of Michigan, have invented a certain new and useful Improvement in Engine-Starters, and declare the following to be a full, clear and exact description of the same, such as will enable others skilled in the art to which it pertains to make and use the same, reference being had to the accompanying drawings, which form a part of this specification.

My invention relates to engine starters and an object of my improvements is to provide an improved apparatus, for use upon an automobile, for starting an internal combustion engine.

I secure this object in the device illustrated in the accompanying drawings in which,

Figure 1, is a side elevation partly in section of an apparatus embodying my invention secured in place upon an automobile, the adjacent portions of the automobile and engine, only, being shown to illustrate the connection of the apparatus therewith.

Fig. 2, is a front elevation of the same.

Fig. 3, is a section on the line C—C Fig. 1 looking from the left of said line.

Fig. 4, is a detail elevation partly in section on the line D—D Fig. 1 looking from the left of said line.

Fig. 5, is a detail view of a part of the apparatus shown in Fig. 1, the parts being shown in a different position.

Fig. 6, is a diagrammatic view showing the electrical connections and circuits.

a represents the engine, b the main shaft and d the cam shaft. c is a gear wheel interposed between a gear wheel on the main shaft and a gear wheel on the cam shaft d. f is a pulley on the outer end of the cam shaft d. g, is a pulley on the starting shaft o hereinafter described and h is a pulley upon a shaft on which turns the cooling fan j. The pulley h and cooling fan j are directly connected.

i is a friction belt extending around the pulleys f g h. n is an arm pivotally secured at one end and at the other end carrying the shaft upon which the pulley h and fan j rotate. k is a spiral spring secured around the pivotal axis of the lever n and bearing at its free end against said lever to oscillate

the same. m is a set screw by which the tension of the spring k may be adjusted. By the spring k and set screw m the tension upon the belt i may be adjusted.

p, is an electric motor and generator hereinafter called simply a dynamo having a shaft o upon the end of which is secured the pulley g. q, is the fly wheel of the engine mounted upon the main shaft b. r indicates a series of gear teeth formed around the periphery of the fly wheel q and somewhat raised above the rest of the periphery of said wheel. s is a gear wheel on the shaft o of the dynamo p. The gear wheel s is adjacent to and in the same plane as the gear teeth r on the fly wheel q, but it does not directly engage said gear teeth. The breadth of the periphery of the gear wheel s is somewhat broader than the teeth r so that said gear wheel extends beyond the plane of said teeth, as shown in Fig. 1. u is a cylindrical rod secured in stationary supports at its ends and extending parallel to the axes of the wheel s and fly wheel q and adjacent to said wheels. t is a gear wheel pivoted and adapted to turn on the rod u. The wheel t is of such a size and so located that its teeth will engage the teeth of the wheel s and the gear wheel r on the fly wheel q when the wheel t is moved into the same plane. Normally the gear wheel t is out of engagement with the gear teeth r and the teeth of the wheel s, as shown in Fig. 1. t² is a sleeve upon the rod u adapted to reciprocate longitudinally of said rod. v is a rod resting in stationary bearings parallel to the rod u and adapted to reciprocate longitudinally through said bearings. One end of the rod v is provided with an arm 4 which extends into a groove in the gear wheel t so that a movement of the rod v shall carry the gear wheel t with it while permitting a free rotation of said gear wheel. At the end of the rod v opposite to that to which the arm 4 is secured is a cam 5 of insulating material adapted to actuate the contact levers of a switch hereinafter described. y, is a cross head rigidly secured to the rod v and sleeved upon the rod u so as to slide longitudinally thereof. w is a compression spring surrounding the rod u and resting at one end against the sleeve t² and at the other end against the cross head y. x is a compression spring surrounding the rod v and bearing

at one end against a stationary support and at the other end against the cross head y . z is a lever pivoted and adapted to oscillate about the stationary pivot 2. 3, is an arm 5 having a fork at its outer end engaging a pin, or lug, upon the cross head y .

By the apparatus just described when the lever z is oscillated to the position shown in Fig. 5, the cross head y is pressed forward 10 bringing a pressure against the sleeve t^2 and tending to press said sleeve forward to slide the gear wheel t into engagement with the gear wheel s and the teeth r on the fly wheel. If the teeth of the gear wheel do not at first 15 engage, there will be the yielding pressure of the spring w always tending to press said wheel forward and when the teeth are made to register, said spring projects the wheel t quickly into engagement with the teeth r on 20 the fly wheel. When the lever z is released the spring w presses the cross head y back and the parts are restored to the position shown in Fig. 1.

8, 9 and 10 are three binding posts arranged in line. 6, is a rocking lever in contact with the center binding post 9 and adapted to contact the binding posts 8 or 10, depending upon which way it rocks.

11, 12 and 13 are three binding posts arranged in line with each other opposite the binding posts 8, 9 and 10. 7, is a rocking lever similar to the lever 6 and contacting the center binding post 12 and adapted to make contact with the binding posts 11 or 15 13 depending upon which way it rocks about its pivot. The inner surfaces of the levers 6 and 7 are concave between their ends and the cam piece 5 on the end of the rod v acts upon said concave surface to rock the levers 40 one way or the other when the rod v is reciprocated.

The rod v is provided with a socket at its end, as shown, and the cam piece 5 is adapted to reciprocate in said socket so as to 45 float between the levers and make an equal contact on both.

14, is a conductor leading from the binding post 10 to the dynamo p . 15 and 16 are storage cells or batteries. 17, is an automatic switch of conventional construction by which a contact 28 is made or broken. 18 represents a ground for the dynamo circuit. The binding post 18 is grounded at 19. The negative post of cell 15 is grounded 55 at 20. 21, is a conductor leading from the binding post 10 through the series coil of the automatic switch 17 and connecting with the conductor 23 which is joined to the binding post 8. 24, is a conductor joining the positive pole of the cell 15 with the binding post 8. 25, is a conductor connecting the positive pole of the cell 16 with the binding post 9. 27, is a conductor joining the negative pole of the cell 16 with the 60 shunt coil of the automatic switch 17. 26,

is a conductor joining the conductor 27 with the binding post 12. 8^a is a strip of conducting material joining the binding posts 8 and 11.

When the rod v is retracted, as shown in Fig. 1, the gear wheel t is drawn out of engagement thus disengaging the dynamo from the fly wheel. The connections and circuits are arranged as shown in Fig. 6 in which the positive pole of the dynamo 75 p is connected through the conductors 14, 21 and 23 with both of the positive poles of the cells 15 and 16 and negative poles of said cells are grounded, one at 20, the other through the conductors 27, 26, pole 80 piece 12, lever 7 and pole piece 13 and the current is being driven by the dynamo in a reverse direction through the cells 15 and 16. When the parts are in the position shown in Fig. 5 and the shaft of the dynamo 85 p is connected through the gear wheel t with the fly wheel, the contact levers 6 and 7 are oscillated at the opposite direction and the binding posts 9 and 10, and 8, 11 and 12 are connected. In this position of the parts 90 the cells 15 and 16 will be connected in series to actuate the dynamo and the rotation of the dynamo shaft o will turn the main shaft of the engine through the gear wheels s and t and the gear teeth r upon the fly wheel. 95 When the lever z is released and the parts returned to the position shown in Fig. 1, the shaft o will be rotated from the engine shaft through the gear wheel on the engine shaft, the gear wheels c and e , the pulleys f 100 and g and the belt i so as to generate the charging current for the batteries.

What I claim is:

1. In an engine starter, an electric starting and charging dynamo, a permanent yielding engagement between said dynamo and engine at one relative speed, and means for temporarily connecting said dynamo to said engine at a different relative speed to drive the same, said yielding connection being adapted to resist relative motion of the connected parts with an approximately constant force that shall not prevent the action of the dynamo to start the engine. 110

2. In an engine starter, an electric starting and charging dynamo, a permanent yielding frictional engagement at one relative speed between said dynamo and engine, and means for temporarily connecting said dynamo to said engine at a different relative speed 120 to drive the same, said yielding connection being adapted to resist relative motion of the connected parts with an approximately constant force that shall not prevent the action of the dynamo to start the engine. 125

3. In an engine starter, a starting and charging dynamo, a permanent yielding engagement between said dynamo and engine adapted to secure one relative speed, and a manually operated means for temporarily 130

connecting said dynamo to said engine at another relative speed to drive the same, said yielding connection being adapted to resist relative motion of the connected parts with 5 an approximately constant force that shall not prevent the action of the dynamo to start the engine.

In testimony whereof, I sign this specification in the presence of two witnesses.

EDWARD S. HUFF.
